Primary Examiner — John M Otte(74) *Attorney, Agent, or Firm* — NSIP Law(57) **CLAIM**

We claim the ornamental design for a display screen or portion thereof with icon, as shown and described.

DESCRIPTION

FIG. 1 is a front view of a display screen or portion thereof with icon showing our new design; and,
 FIG. 2 is an enlarged front view of the icon thereof.
 The dash-dot broken lines depict a display screen or portion thereof that forms no part of the claimed design.
 The dot-dash broken lines in the figures illustrate a boundary of the claimed design and form no part thereof.
